THIEFPROOF CAP FOR TANKS

Edward J. Sullivan, Los Angeles, Calif., assignor
to 7-Star Corporation, Hollywood, Calif., a cor-
poration of California

Application September 12, 1938, Serial No. 229,434

5 Claims. (Cl. 220—86)

This invention relates to a closure for a tank, to prevent theft of liquid from the tank. While the invention can be applied as a closure for a tank for any purpose, it is intended to be used especially as a closure for the fuel tanks of automobiles.

It is a well known fact that many thefts of gasoline from tanks of automobiles, occur.

An object of the present invention is to provide a closure for such tanks, which can be substituted for the ordinary closure, and which will operate to prevent the removal of liquid from the tank, but which will not prevent the free passage of liquid into the tank when filling the same.

The preferred embodiment of the invention involves the use of a sleeve that is inserted and secured in the neck of the tank, and in supplying liquid to the tank it is permitted to flow in through this sleeve. In employing such a practice, there is considerable danger of regurgitation of the liquid through the sleeve. One of the objects of this invention is to provide a construction, which will avoid such regurgitation and spilling of liquid that otherwise might occur in filling the tank.

Fuel tanks such as referred to above, are usually provided with a neck that projects outwardly or upwardly from the upper wall of the tank, and these necks are practically always provided with an inwardly projecting flange that cooperates with the ordinary removable cap to secure the cap in place. The diameters of necks of different tanks vary considerably, although the presence of the inwardly and downwardly turned flange on these necks is practically universal. One of the objects of this invention is to provide a device of this kind, having a construction which will enable it to be used practically universally on tanks having a great range of diameters at their necks; in other words, to provide a thief-proof cap which can be applied to substantially any diameter of neck.

In general, there are two types of necks on tanks of this kind, one of which is a relatively short neck projecting upwardly in an accessible position, and this type of neck is found where the upper wall of the tank is in an accessible or exposed position. There is, however, another style of tank neck in which the neck is curved or of "goose-neck" type. One of the objects of this invention is to provide a construction for the device, enabling it to be applied to either of these types of necks.

Further objects of the invention will appear hereinafter.

The invention consists in the novel parts and combination of parts to be described hereinafter, all of which contribute to produce an efficient thief-proof cap for tanks.

A preferred embodiment of the invention is described in the following specification, while the broad scope of the invention is pointed out in the appended claims.

In the drawing:

Fig. 1 is a perspective showing a portion of the rear end of an automobile indicating a type of tank such as illustrated in Figs. 2 and 3, to which one embodiment of my invention can be readily applied.

Fig. 2 is a vertical section taken through the tank, illustrated in Fig. 1, and showing one of my devices partially in elevation and partially in section, in the act of being inserted in the neck.

Fig. 3 is a view similar to Fig. 2, but represents the neck and the device completely in section, and with the cover or closure of the device in its closed position.

Fig. 4 is a horizontal section taken about on the line 4—4 of Fig. 3, and particularly illustrating the means that I prefer to employ for preventing the passing of a tube down into the tank to reach the liquid within the same.

In practicing the invention, I provide an inner cap to seat on the end of the neck, and this cap has a sleeve that extends down into the neck. This sleeve is constructed at its lower end in such a way as to permit passage of liquid downwardly for filling the tank, but operating as a bar to prevent a tube from being passed down through the sleeve. Associated with the sleeve I provide an expansible locking means or member having means for engaging under the flange of the neck; and also associated with the sleeve I provide a rotary member for effecting the expansion of the expansible member to lock the same under the flange. This construction can be applied to vertical-necked tanks, or to a tank having a goose-neck; but in practice, I prefer to make a slight variation in the details of construction, particularly adapting the same to each type of neck, although the invention is generically present in each embodiment of the invention.

In Figs. 1 to 4, the embodiment of the invention as illustrated, is particularly adapted to be used where the tank 1 of the car has a substantially vertical neck 2. In applying my invention, I provide an inner cap 3 preferably of some rigid

material such as metal, and carrying a sleeve 4 projecting downwardly from the same into the neck 2. The cap 3 is preferably made integral with the sleeve. Under the cap I prefer to provide a relatively soft gasket or cushion in the form of a disc 5 that seats on the upper end 6 of the neck 2. In the present instance the neck 2 is illustrated as having its end face or end 6 constructed so as to present an annular seat beyond which the material is bent downwardly to form a downwardly projecting flange 7. In practice, a flange such as the flange 7, is usually provided with a cam edge 8 or some other means for interlocking the same with a removable cap. Such a cap would be removed and my cap 3 substituted for the same. However, I provide the sleeve 4 with means for engaging under or back of the flange 7 so as to lock the sleeve and inner cap 3 against ready removal. In order to accomplish this, I provide a movable member preferably rotatably mounted on the sleeve, the movement of which will operate to expand the expansible member and lock it securely under or back of the flange. In the present instance, the expansible member 9, as illustrated in Fig. 3, is of substantially V-form, so that it presents two forks or fingers 10 that extend upwardly and diverge from each other in an upward direction. These fingers or forks are preferably sufficiently resilient to enable them to be contracted when they pass the inner face of the flange 7, and are preferably sufficiently resilient to enable them to expand afterwards in the manner indicated in Fig. 2. At a considerable depth within the sleeve 4, and preferably at its lower end, I provide a grill 11 preferably consisting of two bars 12 disposed substantially at right angles to each other and surmounted by angle-form bars 13 (see Fig. 4) which are preferably cast integral with the lower bars 12. At the intersection of the bars 12, a hub is formed to receive a screw 14. This screw passes down through this hub and is threaded through an opening 15 in the body of the expansible member 9. After putting this screw 14 in place, I prefer to upset its end to form an enlarged collar 16 that will prevent the screw from being removed.

With this construction it will be evident that if the screw is tightened up by means of a screw-driver applied in the slot of its head through the upper end of the sleeve, the forks or fingers 10 can be caused to jam themselves securely back of the flange 7.

However, in order to facilitate this operation, I prefer to provide the lower end of the sleeve 4 with two oppositely inclined guide faces 17 against which the inner faces of the forks rest, and below these faces 17 the tapered lower end of the sleeve is formed with slots 18 of slightly greater width than the forks 10. While this is not essential, it gives greater freedom of movement of the body of the expander 9, and facilitates the act of locking it within the neck.

The device preferably includes a movable or removable closure, which is preferably in the form of a cover 19, which may be attached to the inner cap 3, for example, by means of a small hinge pin 20 (see Fig. 3). The under side of this cover 19 preferably carries a gasket 21 of some suitable compressible material.

In order to provide a vent to the atmosphere for the tank, which would be necessary if such a vent were provided in the cap that was removed from the tank, I provide a lower gasket 5 with a port 22, and this port communicates

with a radial slot or passage 23 formed in the upper gasket 21; and in practice, the upper gasket is of slightly larger diameter than the inner cap 3, so as to insure that an outlet 24 will be formed that is always open to the atmosphere.

If desired, means may be provided for latching the cover 19 in its closed position. In order to accomplish this, and also to provide for centering the upper gasket 21, the cover may be provided with a downwardly projecting deep boss or hub 25, and in this boss a ball 26 may be seated within a drilled opening 27 carrying a light coil spring 28 to urge the ball outwardly. This ball is held in place by peening the edge of the bore 27 to a slightly smaller diameter than the ball. When the cover is closed, this ball snaps into a small annular groove 29 formed in the inner face of the sleeve 4.

If desired, the upper side of the cover can carry a name plate 30 carrying legends of any kind. This name plate 30 may be provided with a stem 31 passing downwardly in the opening in the center of the cap and secured in place by a nut 32 seating against the under side of the boss 25. This enables the name plate to be adjusted so as to be right side up, for reading letters or symbols on it.

In filling a tank through a sleeve such as the sleeve 4, if the gasoline flowing in, substantially fills the cross-section of the sleeve, there is no way for air within the tank to escape in sufficient quantity to permit the liquid to flow in freely. This air trapped within the tank would tend to blow out through the sleeve and may tend to produce a regurgitation of the liquid, and sometimes cause it to flow out from the neck. In order to overcome this difficulty, I prefer to provide the upper end of the neck near the cap 3, with one or more air vents 33. These vents open communication between the interior of the tank and the interior of the neck, at a point elevated above a point where the liquid flows from the inserted nozzle of the filling hose; and, of course, these vents should be of sufficient area to permit the air to pass out in such quantity to prevent this regurgitation.

In using my invention, it will be evident that the name plate 30 can carry monograms or the distinctive symbol of a gasoline company, or of the automobile company that manufactured the car.

It is to be understood that the embodiment of the invention described herein is only one of the many embodiments this invention may take, and I do not wish to be limited in the practice of the invention, nor in the claims, to the particular embodiment set forth.

What I claim is:

1. In a thief-proof tank cap for a liquid tank having a neck with an inner flange, the combination of an inner cap to seat on the end of the neck and having a sleeve extending down into the neck, said sleeve constructed at its lower end in the form of a grill to permit passage of liquid downwardly for filling the tank but operating as a bar to prevent a tube from being passed down through the sleeve, an expansible locking member having upwardly extending fingers formed of flexible material capable of flexing inwardly to pass the flange of the neck; the ends of said fingers operating to engage the under side of the flange; and a rotatable member with a thread connection operatively connecting the same to the sleeve and to the fingers for drawing the expansible locking member upwardly in the neck

to force the fingers against the flange, thereby effecting the expansion of the expansible members to lock the same under the flange.

2. In a thief-proof tank cap for a liquid tank having a neck with an inner flange, the combination of an inner cap to seat on the end of the neck and having a sleeve extending down into the neck, said sleeve constructed at its lower end in the form of a grill to permit passage of liquid downwardly for filling the tank but operating as a bar to prevent a tube from being passed down through the sleeve, an expansible locking member having upwardly extending fingers formed of flexible material capable of flexing inwardly to pass the flange of the neck; the ends of said fingers operating to engage the under side of the flange; and a rotatable member with a thread connection operatively connecting the same to the sleeve and to the fingers for drawing the expansible locking member upwardly in the neck to force the fingers against the flange, thereby effecting the expansion of the expansible members to lock the same under the flange, said sleeve having a vent through the wall thereof adjacent the cap for the escape of air up the sleeve when the tank is being filled, and operating to prevent regurgitation of liquid upwardly through the sleeve.

3. In a thief-proof tank cap for a liquid tank having a neck with an inner flange, the combination of an inner cap to seat on the end of the neck and having a sleeve extending down into the neck, said sleeve constructed at its lower end to permit passage of liquid downwardly for filling the tank but operating as a bar to prevent a tube from being passed down through the sleeve, an expansible locking member having yielding flexible members for engaging the under side of the flange of the neck, and a rotary member having a thread connection to the sleeve, located at a depth within the sleeve and capable of being rotated by a tool inserted through the mouth of the sleeve, to force the ends of the

flexible members against the under side of the flange to effect the expansion of the expansible member and lock the same against the under side of the flange.

5. 4. In a thief-proof tank cap for a liquid tank, having a neck with an inner flange, the combination of an inner cap to seat on the end of the neck, and having a sleeve extending down into the neck, said sleeve having grill work at its lower end to permit passage of liquid downwardly for filling the tank, but operating as a bar to prevent a tube from being passed down through the sleeve to reach liquid within the tank, an expansible locking-member with upwardly extending fingers adapted to engage against the under side of the flange, a threaded member having a thread connection to the sleeve mounted at a depth in the sleeve, rotatable in the sleeve and engaging the said expansible member to force the same upwardly and hold the ends of said fingers securely against the under side of the flange.
- 10 15 20 25 30 35 40 5. In a thief-proof tank cap for a liquid tank, having a neck with an inner flange, the combination of an inner cap to seat on the end of the neck, and having a sleeve extending down into the neck, said sleeve having grill work at its lower end to permit passage of liquid downwardly for filling the tank, but operating as a bar to prevent a tube from being passed down through the sleeve to reach liquid within the tank, an expansible locking-member with upwardly extending fingers adapted to engage under the flange, a threaded member mounted at a depth in the sleeve, rotatable in the sleeve and engaging the said expansible member to force the same upwardly and hold the ends of said fingers securely under the flange, the lower end of said sleeve having a seat engaging said expansible member and cooperating with the rotatable member to facilitate the expanding movement.

EDWARD J. SULLIVAN.
